(57) **CLAIM**

The ornamental design for a footboard, as shown and described.

DESCRIPTION

FIG. 1 is a front elevational view of a footboard showing my new design.

FIG. 2 is a left-side elevational view thereof, with the right-side elevational view thereof being a mirror image.

FIG. 3 is a top plan view thereof.

FIG. 4 is a rear elevational view thereof.

FIG. 5. is a bottom plan view thereof.

FIG. 6 is an enlarged fragmentary cross-sectional view taken from the corner of the footboard and looking to the side.

FIG. 7 is an enlarged fragmentary cross-sectional view taken from the corner of the footboard and looking downward.

FIG. 8 is an enlarged fragmentary cross-sectional view taken from above the footboard and looking to the side; and,

FIG. 9 is an enlarged fragmentary cross-sectional view taken from above the footboard and looking downward.

The claimed design does not include any depth for the scroll-like ornamentation at top left and right and the overlapping circle ornamentation along the center of the headboard.

The broken lines depict environment and form no part of the claimed design.
